Primary Examiner — Mary Ann Calabrese*Assistant Examiner* — Mark David Wolfley(74) *Attorney, Agent, or Firm* — Fox Rothschild LLP(57) **CLAIM**

The ornamental design for a seat, as shown and described.

DESCRIPTION

FIG. 1 is a front view of a seat;

FIG. 2 is a right side view of a seat;

FIG. 3 is a top view of a seat;

FIG. 4 is a left side view of a seat;

FIG. 5 is an upper forward perspective view of a seat;

FIG. 6 is a bottom view of a seat;

FIG. 7 is a rear upper perspective view of a seat; and,

FIG. 8 is a rear view of a seat.

The broken lines shown in the drawings depict portions of the seat that forms no part of the claimed design.

1 Claim, 8 Drawing Sheets(56)
